UNITED STATES PATENT OFFICE.

GEORGE W. WEBER AND WILLIAM J. MONTGOMERY, OF CUMBERLAND, MARYLAND.

RAILWAY SAFETY DEVICE.

No. 927,909:

Specification of Letters Patent.

Patented July 13, 1909.

Application filed March 5, 1909. Serial No. 481,220.

To all whom it may concern:

Be it known that we, GEORGE W. WEBER and WILLIAM J. MONTGOMERY, citizens of the United States, both residing at Cumberland, in the county of Allegany and State of Maryland, have invented certain new and useful Improvements in Railway Safety Devices, of which the following is a specification.

10 This invention comprehends certain new and useful improvements in safety devices for railway systems, and relates particularly to means for automatically bringing a train to a standstill, should the engineer pass a 15 danger signal.

The invention has for its primary object a simple, durable and efficient apparatus of this character which may be easily installed on a locomotive, and which will be 20 positive in its operation to vent the train line of the locomotive, and thereby set the air brakes when the tripping devices along the track have been set by the shifting of the block signal, or other signal, to the danger 25 ger position.

With this and other objects in view that will more fully appear as the description proceeds, the invention consists in certain 30 constructions, arrangements and combinations of the parts that we shall hereinafter fully describe and claim.

For a full understanding of the invention and the merits thereof, and to acquire a knowledge of the details of construction, 35 reference is to be had to the following description and accompanying drawings, in which:

Figure 1 illustrates the front portion of a locomotive on a track equipped with the 40 improvements of our invention; Fig. 2 is a top plan view of a portion of the device as mounted upon the locomotive; Fig. 3 is a detail perspective view illustrating the valve handle and a portion of a spring co-acting therewith; Fig. 4 is a sectional view illustrating the parts shown in Fig. 3, in assembled 45 relation; Fig. 5 is a detail sectional view of a form of valve which may be employed; Fig. 6 is an enlarged perspective view of the 50 apparatus; Fig. 7 is a detail sectional view of a portion of the mechanism along the track; and, Fig. 8 is a similar view illustrating the lower end of the trip lever.

Corresponding and like parts are referred 55 to in the following description and indicated

in all the views of the drawings by the same reference characters.

In carrying out our invention, we secure to some convenient point on the locomotive, preferably one end of the pilot bumper 1, a support 2 which, in the present instance, consists of a vertically disposed plate 3 bolted or otherwise secured at its upper end to the rear side of the bumper 1 at one end of the latter, a vertically disposed plate 4 extending at right angles to the plate 3, and a horizontally disposed plate 5 extending inwardly from the upper edge of the plate 4.

6 designates a brace which is preferably secured at one end to the plate 4 near the lower end thereof, and which is secured at its inner end (not shown) to a convenient portion of the locomotive.

7 designates a valve which may be of any desired construction or design, but which is preferably of the type illustrated in Fig. 5, having a tapered turning plug 8 spring held on its seat and provided with an upper end 9 which projects upwardly through the horizontally disposed plate 5. One port of the valve 7 opens to the atmosphere, while the other is connected by a flexible hose coupling 10, or the like, to the train line 11, at any suitable point. Obviously, the opening of the valve 7 will vent the train pipe and set the air brakes, thereby bringing the locomotive or train to a standstill.

A contractile spring 12 is mounted upon the horizontally disposed plate 5 of the support 2, one end of said spring being connected to a stud 13 which projects upwardly from the plate, and the other end of said spring being coiled upon itself as indicated at 14, and longitudinally slotted as at 15. This last named end of the spring embraces an apertured lug 16 formed on one side of a valve handle 17 which is adapted to be slipped over and secured upon the polygonal upper end 9 of the plug 8. A pin 18 is designed to be inserted through the lug 16, the pin and the coiled end 14 of the spring being held in place by a set screw 19 working through the lug 16 so as to detachably secure the spring to the valve handle.

The handle 17 is normally held in the position illustrated in Fig. 6 by means of a hook 20 which is pivotally carried on the outer face of the plate 4. The lower end of the hook or detent 20 is engaged by the upper arm of a lever 21, said lever being fulcrumed

on the plate 4 as at 22. The lower arm of the lever 21 is engaged by the upper arm of a lever 23 also fulcrumed on the plate 4 and projecting downwardly below the same. 5 The movement of this lever 23 is limited in one direction by means of a stud 24 projecting outwardly from the vertically disposed plate 4. Obviously, the movement of the lever in the opposite direction will rock the 10 lever 21 and consequently disengage the hook 20 from the valve handle 17, permitting the contractile spring 12 to act and open the valve.

In order to automatically trip the lever 23, 15 we have provided track devices which are under the control of the signal operator, and which are preferably actuated simultaneously with the signal. These track devices include a trip lever 26 having a relatively 20 wide head or free end 25 designed to be extended into the path of movement of the lower arm of the lever 23 so as to engage the same and set the brakes. The head 25 is laterally widened, as shown, so as to compensate 25 for any swaying of the locomotive. The lever 26 is secured to a longitudinally extending shaft 27 journaled to turn about its longitudinal axis in bearings or standards 28 projecting upwardly from a base plate 29 secured 30 in any desired way alongside of the track. The movement of the trip lever 26 in a vertical plane, as shown, is limited in one direction by means of a stop bar 30 which is secured to the rear side of two of the standards 35 28, and which is designed to engage with the recessed end 31 of the trip lever. The shaft 27 carries a crank 32 provided with a laterally extending wrist pin 33, and working in slots 34 extending longitudinally in a slide or 40 actuating device 35. This actuating device 35 is secured to one of the rods 36 of an interlocking block signal system or the like (not shown), and is designed to be actuated simultaneously with the signal mechanism. 45 The crank 32 extends downwardly in a vertically disposed longitudinally extending slot 37 formed in the actuating device 35.

In the practical operation of our railway safety device, the valve handle 17 is moved 50 by hand, or by the use of any desired tools, to the position illustrated in Fig. 6, placing the contractile spring 12 under tension and closing the valve. The handle is held in this position by engagement with the hook 20. The 55 safety mechanism carried by the locomotive, is thus set. So long as the signal shows white, it will be understood that the trip lever 26, co-acting with such signal, remains in lowered position where it will not strike the 60 downwardly projecting lower arm of the lever 23. Should the signal be changed to green, still no movement would be imparted to the trip lever 26, owing to the lost motion connection between the actuating device 35 65 and the crank 32 effected through the instru-

mentality of the side slots 34. When, however, an additional movement is imparted to the rod 36 by the movement of the signal to show red, indicating that the train should come to a stop, the actuating device 35 will 70 be positively engaged by the crank 32, and thereby partially rotate the rod 37 in a direction to throw the lever 26 up into an operative position where it will engage the lever 23 of the next locomotive which comes along, 75 and thereby disengage the lever 20 from the valve handle 17. This permits the spring 12 to act to throw the valve handle around in a direction to open the valve and exhaust the air pressure from the train line, thereby setting 80 the brakes and bringing the train to a standstill.

If desired, the operative parts that are carried by the locomotive, may be protected from the elements, or from being tampered with, by means of a cover 37 hinged to the horizontally disposed plate 5 designed to close down over the valve-actuating spring and handle, such cover being provided with an extension 37^a which, in the closed position 90 of the cover, projects downwardly over the hook 17. It is clear that the tension of the spring 12 pressing the handle 17 against the hook 20 prevents the handle from being released by any jars or blows other than the 95 blow upon the lever 23.

It is to be understood that the devices on the locomotive are suspended high enough above the rail to clear all necessary obstructions alongside the track; that they will not interfere with the working of any part of the locomotive; that they are so situated on the locomotive as to be in nowise liable to be accidentally operated by any foreign substance which might happen to be picked up by the 100 wheels of the locomotive, or by the suction of the air, when running at high speed. It is also to be understood that the tripping device may be connected to switches, drawbridges, crossing gates or the like, by a direct communication, without using the slide 110 35 which is designated for connection with the semaphore.

While the invention is herein shown as applied to a locomotive, it is to be understood 115 that the invention is equally applicable for use on electric cars, or in fact on any cars or other vehicles using air brakes.

Having thus described the invention, what is claimed as new is:—

1. The combination with a train line, of a valve connected thereto and arranged to exhaust the air pressure therefrom, a handle connected to said valve, a support for said valve, a contractile spring connected at one end to the support and at its other end to the valve handle, and arranged to move the valve handle in a direction to open the valve, a hook pivotally mounted upon the support 125 and designed to engage the valve handle to 130

hold the valve closed, a lever fulcrumed intermediate of its ends on said support, one arm of said lever engaging the hook, another lever fulcrumed on the support, one arm of 5 said last named lever engaging the other arm of the first named lever, and the other arm of said first named lever projecting below the same, and track devices arranged to trip said last named lever by engagement with the arm 10 thereof.

2. An apparatus of the character described, comprising a support embodying a vertically disposed plate designed to be secured to the pilot bumper of a locomotive, a 15 second vertically disposed plate extending substantially at right angles to the first named vertical plate, and a horizontally disposed plate extending inwardly from the upper edge of said second named vertical plate, 20 a valve, a train line with which said valve has operative connection to vent the same, said valve being secured to the support underneath the horizontally disposed plate thereof and embodying a turning plug projecting upwardly through said horizontally disposed plate, a handle mounted upon the upwardly projecting end of the plug and arranged to sweep over the upper surface of the horizontally disposed plate, spring means 25 tending to move said handle in a direction to open the valve, a hook pivotally mounted upon the second vertically disposed plate of the support and arranged to engage said handle to hold the valve closed, a lever fulcrumed on said last named plate and arranged 30 upon movement in one direction to disengage the hook from the handle, and track devices arranged to trip said lever.

3. In railway safety devices of the character described, a train line vent valve, a handle connected thereto to control the same,

said handle being formed with an apertured lug, a support for said valve, a spring connected at one end to the support, the other end of said spring being slotted to embrace 15 the lug of the handle, and being curled upon itself, a pin extending down through the lug and curled end of the spring, means for holding said pin in place to secure the spring to the lug, means for holding the handle with 50 the valve in closed position and with the spring under tension, and track devices arranged to automatically effect the disengagement of said holding means from the handle.

4. In an apparatus of the character described, track devices embodying a trip lever, a shaft carried by said lever, a crank secured to said shaft, supports in which said shaft is journaled, a wrist pin carried by said crank, 60 an actuating device formed with a longitudinal slot accommodating said wrist pin, and an actuating rod connected to said actuating device.

5. In an apparatus of the character described, track devices embodying a trip lever, an actuating shaft upon which said lever is mounted, supports in which said shaft is journaled, a crank secured to said shaft, an actuating device formed with a vertically 65 disposed longitudinal slot accommodating said crank and with a side slot, a wrist pin secured to the crank and working in said side slot, and a signal-actuating rod connected to said actuating device.

In testimony whereof we affix our signatures in presence of two witnesses.
